UNITED STATES PATENT OFFICE.

EMMETT S. WEBSTER, OF MISHAWAKA, INDIANA.

LOOM.

1,183,930.

Specification of Letters Patent.

Patented May 23, 1916.

Application filed September 27, 1915. Serial No. 52,946.

To all whom it may concern:

Be it known that I, EMMETT S. WEBSTER, a citizen of the United States, residing at Mishawaka, in the county of St. Joseph and 5 State of Indiana, have invented certain new and useful Improvements in Looms, of which the following is a specification.

The invention relates to an improvement in looms and more particularly to a loom 10 adapted for operation for the instruction of one desiring to be taught weaving.

The improved loom is adapted throughout for manual operation and adjustment and constructed with a view to enabling the 15 pupil to understand the different steps in the weaving process and to readily and conveniently control the various operations to reduce the character of the weave desired.

In structure the loom involves a frame 20 supporting at opposite ends the warp beam and cloth roll frictionally held against operation except through manual control and the intermediate harness and reed, and a fringe weaving support to be used in forming fringe upon the woven fabric, the harness consisting of a plurality of separately controlled heddle frames manually operated so that by actuating said heddle frames in 25 a predetermined order a particular kind of weaving may be done.

The invention in the preferred form of 30 details will be described in the following specification, reference being had particularly to the accompanying drawings, in 35 which:

Figure 1 is a plan view of the improved loom; Fig. 2 is a side elevation of the same; Fig. 3 is a sectional view on the line 3—3 of Fig. 1; Fig. 4 is a sectional view on the line 40 4—4 of Fig. 1; Fig. 5 is a sectional view on the line 5—5 of Fig. 1.

The improved loom comprises a main frame 1 having end uprights 2 and an intermediate harness frame 3 all of which may be 45 of any usual or preferred construction. Mounted between the end uprights 2 at one end of the frame is the warp beam 4, while a cloth roll 5 is mounted between the uprights at the opposite end of the frame. 50 The shafts on which the respective beam and roll are mounted are provided at one end beyond one of the uprights with set screws 6 whereby the particular uprights may be brought into frictional engagement 55 with the beam or roll so as to normally hold these parts against accidental rotation and

yet permit them to be manually turned by the hand when desired. This insures a sufficiently tight holding of the threads and yet permits a winding up of the completed fabric as may be found necessary. 60

Mounted in the harness frame 3 is the harness comprising in this instance four independent heddle frames 7. The heddle frames are provided with the customary 65 eyes through which the warp strands 8 of the fabric are threaded and each heddle frame is connected at the opposite sides of the upper end with cables or cords 8' which pass over rollers 9 appropriately mounted 70 in the harness frame and are both terminally connected to a depending cord or cable 10 terminating in a hand hold, shown in the form of a ball 11. The respective cables 10 of the heddle frames are of different 75 lengths so that the balls are pendent in spaced relation to permit a particular one to be readily grasped and operated without interference. The heddle frames are maintained in their inoperative or lowered position by coil springs 12 terminally secured to the respective ends of the bottom of the frame and centrally secured at 13 to the main frame. By the connection of the heddle frames as described the movement of the 85 heddle under the pull on the particular cable 10 will insure an even and regular movement of such frame, both in its upper as well as in its downward movement, the latter being insured by the balanced action 90 of the springs.

Arranged intermediate the cloth roll and a harness frame is the usual reed 14 mounted for the usual movement and needing no further detail described herein. The shuttle 15 95 is of the hand type, and the weft thread 16 wound on said shuttle is woven between the warp threads by hand, obviously by shifting the shuttle back and forth as is well understood. 100

For providing a fringe or the like upon the woven fabric I secure to one of the end uprights 2 of the main frame a reel 17 on which is wound a suitable length of wire or other appropriate strand 18. This strand 105 is passed from the reel 17 over the warp beam, between two of the heddles of the harness, and winds about the cloth roll. The strand 18 is spaced from the immediately adjacent warp thread, that is the edge 110 thread a distance desired for the depth of the fringe, and is placed between the ap-

propriate heddles as will maintain and guide the wire strand in this position. The wire strand hereinafter termed the fringe guide is of course not raised and lowered by the harness and in the weaving operation the shuttle is passed over and around said fringe guide as said shuttle is moved back and forth providing a thread projection at the edge of the fabric in the form of loops which, severed or not as desired from the fringe. It is obvious of course the fringe of the guide may be located at any desired distance from the immediately adjacent warp thread to insure any appropriate 15 depth of fringe.

The improved loom by proper operation of the heddles of the weaving may be secured through the use of two of the heddle frames, while for weaving double or tubular cloth the harness is operated by manually actuating the harness in the following order. The first and second heddles, the first, second and third heddles, and the first, second and fourth heddles and repeat; 25 while for weaving twill cloth the harness is operated in direct sequence as first, second, third and fourth and repeat.

The improved loom is designed primarily for teaching weaving, and may be thus 30 stated to be a school room loom, and its essential characteristics are the means for maintaining a proper tension upon the warp threads, through the frictional engagement of the thumb screws described, the selective and manual operation of the heddle frames, and the fringe guide in the use of which a fringe of any desired depth may be readily and conveniently secured.

In the essential features particularly 35 herein described it is to be understood that the usual structure of such parts as in ordinary looms is employed.

Copies of this patent may be obtained for five cents each, by addressing the "Commissioner of Patents, Washington, D.C."

What is claimed is:

1. A hand loom involving a main frame, a harness frame mounted thereon having an upper structure extending to one side of and beyond the main frame, a plurality of heddle frames arranged in the harness frame, means for returning and normally holding the heddles in a lowered position, independently operable cables connected to each of said heddles and passing over pulleys mounted on said upper structure of the harness frame, one of said pulleys being mounted adjacent the outer end of the extended portion of said frame, and depending hand-pull terminals connected with each of said cables adjacent the end of said extended frame. 45 50 55

2. A hand loom involving a main frame, a harness frame mounted thereon having an upper structure extending to one side of and beyond the main frame, a plurality of heddle frames arranged in the harness frame, means for returning and normally holding the heddles in a lowered position, independently operable cables connected to each of said heddles and passing over pulleys mounted in said upper structure, one of said pulleys being disposed adjacent the 60 end of the extended portion of said upper structure, and depending hand-pull terminals connected with each of said cables to one side of and remote from the main frame, said terminals being of relatively different 65 lengths whereby to relatively distinguish the heddles to facilitate selective operation 70 75 thereof.

In testimony whereof I affix my signature in presence of two witnesses.

EMMETT S. WEBSTER.
